Attorney

UNITED STATES PATENT OFFICE.

BENTON L. JENNINGS, OF MANHATTAN, KANSAS.

CLEVIS.

SPECIFICATION forming part of Letters Patent No. 336,484, dated February 16, 1886.

Application filed October 22, 1885. Serial No. 180,660. (No model.)

To all whom it may concern:

Be it known that I, BENTON L. JENNINGS, a citizen of the United States of America, residing at Manhattan, in the county of Riley 5 and State of Kansas, have invented certain new and useful Improvements in Clevises; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention relates to certain new and useful improvements in clevises, the object of my improvement being to provide an improved clevis, the parts of which are all permanently attached to each other in such a manner that 20 the clevis can be readily attached to the implement and a draft-ring removed therefrom; and to this end my invention consists in a clevis, the construction of which will be hereinafter fully set forth, and specifically pointed 25 out in the claims.

In the accompanying drawings, which illustrate my invention, Figure 1 is a side view showing the clevis closed in full lines and open for the removal of a draft-ring in dotted lines. 30 Fig. 2 is a sectional view. Fig. 3 is a front view. Fig. 4 is a side view or modification of my invention. Fig. 5 is a front view of Fig. 4. Fig. 6 is also a front view of a modification, and Fig. 7 is a side view of the same.

35 A represents the upper portion of the clevis, which is provided at its front end with a downwardly-projecting portion, A', which is curved, as shown, and provided at its lower end with upwardly-projecting members A".

40 As shown in Figs. 1, 2, and 3, the downwardly-projecting portion A' is bifurcated, so as to provide a recess, a, between the side walls of the portion A', thus making the upwardly-projecting members A" separate from 45 each other.

45 Between the downwardly-projecting members A', within the recess a, is pivotally secured the lower portion of the clevis B, which is secured thereto by pivot-pins b, and the 50 front of this member or portion B of the clevis is cut away, so as to fit within the recess a, so that it can play within the recess a. Adjacent

to the members A' A" the portion B is provided with shoulders C. The upper bar or portion, A, is provided near its rear end with a downwardly-projecting pin, D, the lower 55 end of which is reduced in diameter, so as to provide a shoulder, d, and over this reduced portion the pivoted section B will fit, the end of said pivoted section being provided with a 60 perforation, e.

As shown in Fig. 4, the pivoted section B is bifurcated and pivoted to a downwardly-projecting portion of the clevis, which has but a single upwardly-projecting member, A". 65

As shown in Figs. 6 and 7, the parts A and B may be cut away at opposite sides and secured to each other by a pivot.

To attach my improved clevis to an implement, a straight vertical hole is bored through 70 the same of sufficient diameter to receive the pin D, this being all that is necessary to attach the clevis thereto.

When it is desired to place a draft-ring in position, the pivoted section B is moved to the 75 position shown in dotted lines, and said ring is passed to the upper side of the clevis, and, coming in contact with the upper end of said pivoted section, removes said end forwardly, so as to elevate its rear end and bring it over 80 the lower end of the pin B, the draft-ring being held in position between downwardly-projecting portions A' and the finger or fingers A". Thus it will be seen that the draft-ring will hold the pivoted section upon the pin, 85 and its displacement cannot be effected as long as said draft-ring remains in the position hereinbefore described.

It will be noted that by means of my improved clevis the attachments—such as pins 90 or bolts—for securing the clevis to the implement are dispensed with, and that the parts of my improved clevis are permanently attached to each other.

I claim—

1. The improved clevis herein described, consisting of an upper portion which is bent downwardly at its forward end and again upwardly, as shown, a pivoted section attached to the lower forward end of the same, and provided with an upwardly-extending portion attached thereto, and a pin rigidly attached to the upper member of the clevis and adapted to enter a perforation in the rear end of the piv-

oted section, substantially as shown, and for the purpose set forth.

2. The improved clevis herein described, consisting of the portion A, which is bent downwardly at its forward end, and provided with upwardly-projecting fingers A", and at its rear end with a downwardly-projecting pin, in combination with a section, B, pivotally secured to the lower end of the upper portion

which is adapted to fit over the end of the pin D, substantially as and for the purpose set forth.

In testimony whereof I affix my signature in presence of two witnesses.

BENTON L. JENNINGS.
